COMBINATION FASTENING DEVICE

Anders C. Olsen, Forest Hills, N. Y.

Application March 7, 1945, Serial No. 581,499

3 Claims. (Cl. 72—118)

1

This invention relates to improvements in fastening devices and is more particularly concerned with the provision of fastening devices for securing covering material to a support which is in a plane substantially at right angles to the plane of the covering material. One particular application of the present invention is found in the erection of a plastering base or sheathing in the original construction or remodelling of building walls and ceilings.

Among the objects of the present invention is to provide a novel fastener or clip designed to be positively and yieldingly engaged in a unique manner with a supporting member of inexpensive construction whereby any type of covering material may be laid at random and securely fastened at points intermediate its edges to such a support, against which the covering material bears.

Another object is to hold the covering material against structural supporting members under slightly yielding tension, thereby allowing for the stresses and strains induced by expansion and contraction or by settling or other movement of the building.

A further object is to provide a more economical and durable means of attaching plastering base or sheathing material to a support in the erection of low-cost buildings.

Further objects are to provide building construction of the foregoing type which may be erected with maximum simplicity, efficiency and economy.

Other features and advantages of the invention will become more readily apparent in the following detailed description and accompanying drawing in which

Fig. 1 is a fragmentary view, in perspective, of one form of supporting member embodying the present invention;

Fig. 2 is a perspective view of one form of fastener or clip designed, in accordance with the present invention, for locking engagement with a supporting member, such as illustrated in Fig. 1;

Fig. 3 is an enlarged plan view of a supporting member and the shank portion of a fastener illustrating an initial step in effecting cooperative engagement therebetween;

Fig. 4 is a view similar to Fig. 3 illustrating a successive step in the engagement of a fastener with a supporting member;

Fig. 5 illustrates the final operative position in the fastening of a covering material to a structural supporting member;

Fig. 6 is a perspective view of another form

of fastener or clip embodying the present invention;

Fig. 7 is an end view in elevation of the member shown in Fig. 6;

Fig. 8 is a fragmentary view, in perspective, of another form of supporting member embodying the invention;

Fig. 9 is a fragmentary view, in perspective, of a portion of a wall or ceiling erected in accordance with the present invention; and

Fig. 10 is a fragmentary view, in perspective, of a double wall or partition erected in accordance with the present invention.

Referring to the drawing, Fig. 1 shows one form of supporting member that may be used in the practice of the invention. In this form, the supporting member, indicated at 10, comprises a strip of sheet metal or other material of suitable strength and rigidity bent along its longitudinal median line, as indicated at 11, to provide spaced webs 12 and 13 extending in the same general direction from the bend and in substantially parallel planes.

The webs 12 and 13 terminate respectively in flanges 14 and 15 which are bent inwardly at similar acute angles with respect to their respective webs. As best shown in Fig. 3, the flanges 14 and 15 terminate in close proximity to each other, as at 16, preferably at a point centrally between the opposing webs, thus forming a mouth portion therebetween having converging jaws 17 which are in resilient relation to one another so as to be adapted to be sprung open and then closed to engage the fasteners of the present invention, as will be more fully explained hereinafter. The thus formed structural supporting member 10 may be strong and rigid enough and of any desired width and length appropriate for use in any suitable manner, for example, to serve as a non-reinforced, vertical stud in place of the usual channel member in the construction of walls, or as a properly suspended but non-reinforced runner in the construction of new or renovated ceilings.

In conjunction with a supporting member formed, for example, like the above described member 10, there is provided a suitable form of fastener or clip adapted to be locked in engagement with the supporting member. One such form of the fastener or clip, generally designated by the reference numeral 20, is shown in Fig. 2 and comprises a substantially U-shaped member fabricated from a relatively narrow strip of sheet metal or other material of suitable strength and resiliency. As shown, the fastener or clip is com-

45

50

55

posed of a narrow, elongated head 21 terminating in a shank portion which, in this embodiment, comprises a pair of spaced parallel legs 22 and 23 extending in the same general direction substantially at right angles to the head and lying substantially in the same plane therewith.

The legs 22 and 23 each are provided with a plurality of suitably formed interruptions located between the head and their outer ends. In this instance, the interruptions are of a serrated nature formed by a series of spaced pairs of recesses 24. The opposing recesses 24 of each pair converge toward each other and are symmetrical with respect to the longitudinal axis of the leg. Each recess terminates in a laterally extending shoulder 25 to complete the serrated formation. The legs each terminate in a point 26 shaped substantially like a spear-head and centrally located with respect to the lateral margins of the leg.

The manner in which the above described forms of supporting member and fastener embodying the present invention are designed to cooperate with each other in securely mounting plastering base or sheathing material in a plane substantially at right angles to the plane of the supporting member is clearly illustrated in Figs. 3 to 5. The shank portion or spear-head pointed legs of the fasteners or clips 20 will readily pierce an imperforate material, such as gypsum or fibre insulation board, or may be readily inserted through openings in a reticulated type of material, such as expanded metal lath, that may comprise the plastering base or sheathing. For any given thickness of any such material, the shank portion or legs will be of sufficient length to project from the inner face thereof a distance sufficient to present a number of the spaced pairs of shoulders, barbs or saw-teeth 25 on each of the legs. In the case of a relatively thick, imperforate sheet, for example, a gypsum or fibre insulation board, such as is indicated at 40, the legs 22 and 23 of the fastener or clip 20, when driven through the material, will extend beyond the inner face 41 thereof and the head or bearing portion 21 of the fastener will be positioned substantially flush with the outer face 42 of the material.

In the practice of my invention, the legs of a clip 20 are directed into the converging jaws 17 of the mouth portion of the supporting member 10, as shown in Fig. 3. As the spear-headed ends 26 of the legs 22 and 23 contact the resiliently spaced converging jaws 17 and are directed inwardly toward the constricted throat of the mouth at 16, the diverging sides of the spear-head ends 26 force the jaws apart until the mouth and throat of the supporting member is sprung open sufficiently to permit the widest portion of the legs at the shoulders 25 to pass therethrough. Thus, the resiliently spaced jaws and their respective webs 12 and 13 are placed under tension, as illustrated in Fig. 4. When the first pair of shoulders 25 on each leg clears the ends of the jaws 17, this tension is relieved and the jaws tend to resume their normal, unsprung relation, whereupon they slide into closing position in the recesses 24 behind the shoulders 25. This process may be repeated, of course, until the fastener shank portion is locked in fixed position between the opposing webs of the supporting member at any selected point along the length of the shank.

In lieu of the fastener or clip having the form above described, other forms of fasteners may be provided for use similarly in conjunction with a supporting member, such as the member 10.

One such alternative form of fastener is shown in Fig. 6 and generally designated by the reference numeral 50. In this embodiment, the fastener 50 may comprise a substantially T-shaped member formed from sheet metal or other material of suitable strength and resiliency. As shown, the fastener consists of an elongated head or bearing portion 51 and a shank portion 54 extending substantially at right angles to the head and lying in a transverse plane located centrally with respect to the longitudinal ends of the head portion.

The head portion 51 may comprise oppositely directed co-planar wings 52 and 53 formed by splitting or dividing the head portion into strips of equal width and then bending these strips in opposite directions at right angles to the shank portion 54. Instead of thus providing a T-shaped fastener, the splitting or dividing of the head portion into separable wings may be omitted, whereby the head portion will extend entirely in one direction relative to the shank, thus forming an L-shaped fastener.

The shank 54 is provided with a plurality of spaced interruptions 56 between the head portion 51 and the outer end 55 thereof. These interruptions may take the form of double rows of spaced lugs, one row being struck or punched out of one side of the shank portion and the other row being similarly struck or punched out of the opposite side of the shank portion, as best shown in Fig. 7, or they may be in the form of bosses, detents or other suitable types of spaced protuberances or projections. In any case, projecting interruptions 35 are provided extending from both sides of the shank portion of the fastener for resilient locking engagement with the jaw or jaws of a supporting member at selected points along the shank, when the fastener is engaged with the supporting member in the attachment of covering material thereto, as previously described in connection with the U-shaped fastener 20.

The extent to which the shank portion or portions of each of a plurality of fasteners or clips 20 or 50 must be inserted into and through the mouth of one of a number of spaced supporting members 10 is determined by the thickness of the covering material that must be accommodated for secure attachment to the supporting members. 50 The process of engaging each fastener within the mouth of a supporting member is repeated until a desired number of the fasteners are spaced at desired intervals along the length of each of the spaced supporting members to which each section 55 of the covering material is to be secured. The resultant cooperative interlocking of the converging jaws 17 with a pair of shoulders or barbs 25 on each of the fastener legs, in the case of the fastener 20, or with a pair of opposing lugs 56 on the shank 54, in the case of the fastener 50, effectively prevents the accidental withdrawal or release of either of these types of fasteners from their fixed position with respect to the supporting member.

65 One advantage of providing for the shank portion of the fasteners or clips to be inserted any required distance within the supporting member necessary to accommodate the thickness of the plastering base or sheathing material being attached thereto is that plastering base or sheathing materials of widely varying thicknesses may be accommodated by fasteners having shank portions of one standard dimension.

An additional advantage in the cooperative 75 engagement thus afforded between the structural

supporting members and fasteners of my invention is that the inherent resiliency of the web portions of the supporting members permits a "floating" attachment of the covering material thereto, even though the fasteners are securely engaged with the converging jaws of the mouth portions thereof. For example, when the combination fastening device of my invention is utilized for mounting a plastering base in the erection of a wall or ceiling, this "floating" feature will effectively compensate for any stresses and strains caused by expansion or contraction forces or by settling or other movement of the building, thus materially reducing or entirely eliminating the unsightly cracks that may otherwise appear in the outer plaster coating of the finished construction.

In the erection of a wall, for example, the supporting members 10 serving as studs are positioned extending from the floor to the ceiling and spaced apart say 16 inches on center. As shown in Fig. 9, a section of the plastering base or sheathing material 40 may then be laid across a number of the spaced studs and manually held thereagainst until securely attached thereto by using a number of either form of the fastener or clip previously described. Each of the fasteners, in turn, is driven through the covering material and the shank portion of each, emerging from the inner face 41 of the covering material, is engaged with the subjacent stud, as already fully described. It is a comparatively easy matter to properly apply each of the fasteners so that the shank thereof will be in alignment with the mouth of the stud. A plurality of these fasteners may be spaced apart a distance sufficient to securely mount the covering material on the subjacent structural support. It will thus be seen that the fasteners or clips may be rapidly driven into place and engaged with the supporting members with a maximum of accuracy and a minimum of effort so that the covering material may be erected economically and efficiently.

In the case of double wall or partition construction, successive studs 10 may be reversed with respect to each other so that the covering material may be laid up on opposite sides and securely attached to the intermediate studs comprising the structural support therebetween. With this type of construction, the attachment of the covering material to the supporting studs spaced 16" apart will occur along each side at horizontally spaced intervals of approximately 32". In order to provide a somewhat stronger double-wall construction wherein the attachment of the covering material to the intermediate studs will occur at horizontally spaced intervals of only 16" along each side, as may be desired in certain instances, I may use the form of supporting member shown in Fig. 8. This supporting member, generally designated by the reference numeral 60, is substantially S-shaped in cross section and may be formed from sheet metal or other material of suitable strength and resiliency which is return-bent, as at 61 and 62, to provide spaced webs 63, 64 and 65. The webs 63 and 65 lie in substantially parallel planes and extend for equal distances but in opposite directions to one another. The intermediate web 64 lies in a plane which forms acute angles with the substantially parallel planes of the webs 63, 65.

The webs 63 and 65 terminate respectively, at their free ends, in flanges 66 and 67 which are bent inwardly at a similar acute angle with respect to their respective webs. Both flanges 66

and 67 terminate in close proximity to the web 64, but on opposite sides thereof, thus forming along each margin of the member 60 a mouth portion having a resilient converging jaw. The resilient jaw of each of the opposing mouth portions is adapted to be sprung open and then closed to engage the fasteners of the present invention in the manner already fully described. Any one of the several forms of fasteners set forth above may be used with equal facility in the attachment of suitable covering material to the spaced supporting members 60 utilized, as in Fig. 10, in the erection of a double-wall type of construction.

15 The constructions illustrated in Figs. 9 and 10 may be completed either by applying the usual coats of plaster to the erected plaster base or by applying any desired type of covering to the erected sheathing.

20 The terms "plastering base" and "sheathing" as used herein are intended to cover any type whatsoever of covering material suitable either for the reception of a coating of plaster or for the application thereover of wallpaper, interior 25 paneling or exterior siding, and may include materials such as expanded metal lath, paper-backed wire lath and perforate or imperforate boards or panels having a fibrous or cementitious core. Inasmuch as the combined fastening 30 means of the present invention may be used in connection with different types of "plastering base" or "sheathing" material of widely varying thicknesses, it will be understood that the dimensions of the hollow structural supporting members and of the fasteners or clips may be varied accordingly to accommodate such different thicknesses or different modes of application.

I claim:

1. In the combination of spaced tubular supporting studs having resilient jaws and a plastering base secured to said studs by fasteners adapted to be gripped within said jaws, the improvement comprising fasteners each made of flat sheet material and comprising a head and a pair 45 of spaced legs located substantially in the same vertical plane, said legs being serrated between said head and their outer ends for resilient locking engagement within said jaws, the shoulder surfaces of the serrations being disposed substantially at right angles to the vertical plane in which the legs are disposed.

2. In the combination of spaced tubular supporting studs having resilient jaws and a plastering base secured to said studs by fasteners adapted to be gripped within said jaws, the improvement comprising fasteners each made of flat sheet material and comprising a U-shaped member having the legs thereof pointed at their free ends and serrated along a portion of their 55 lengths for resilient locking engagement with said jaws, the legs of said U-shaped member being disposed substantially in a vertical plane and the shoulder surfaces of the serrations being disposed substantially at right angles to the vertical plane in which the legs are disposed.

3. In combination, studs to support a plastering base or the like, each of said studs comprising spaced webs integrally joined together by an intermediate web, said webs terminating at their 60 free ends in inwardly bent flanges forming resilient jaws along the margins thereof, a plurality of fasteners adapted for spaced engagement with said studs for securing said plastering base or the like thereto, said fasteners each comprising a U-shaped member having the legs thereof

pointed at their free ends and serrated along a portion of their lengths for resilient locking engagement with said jaws, the legs of said U-shaped member being disposed substantially in a vertical plane and the shoulder surfaces of the serrations being disposed substantially at right angles to the vertical plane in which the legs are disposed.
